Filed Feb. 16, 1971, Ser. No. 115,915

Term of patent 14 years

Int. Cl. D2—02

U.S. Cl. D2—27

FIG. 1

FIG. 2

FIG. 3

FIG. 1 is a front perspective view of a combined chest and neck protector showing my new design:

FIG. 2 is rear perspective view thereof in open position:

FIG. 3 is a rear elevational view of a second embodiment in closed position, the front being the same as that of FIG. 1.

The characteristic feature of my design for a chest and neck protector resides in the combination of the half oval front panel and the elongated inset pocket all is shown on the drawing.

I claim:

The ornamental design for a combined chest and neck protector, substantially as shown and described.
